UNITED STATES PATENT OFFICE.

FREDERIC W. C. SCHNIEWIND, OF NEW YORK, N. Y.

CAR CONSTRUCTION.

976,932.

Specification of Letters Patent. Patented Nov. 29, 1910.

Original application filed October 24, 1907, Serial No. 398,901. Divided and this application filed January 7, 1909. Serial No. 471,046.

To all whom it may concern:

Be it known that I, FREDERIC W. C. SCHNIEWIND, a citizen of the United States of America, residing in the city, county, and 5 State of New York, have invented a certain new and useful Improvement in Car Construction, of which the following is a true and exact description, reference being had to the accompanying drawings, which form a 10 part thereof.

The present invention relates to the construction of a car or transporting device adapted to have heavy material loaded on and unloaded from it, and the construction 15 disclosed was primarily devised for use in handling hot coke which is discharged from coke oven retorts directly onto the car and is quenched thereon, and is then dumped from the car into railway cars for transportation 20 or into storage receivers.

The object of the present invention is to provide a car construction which is simple, strong and durable, and which can be readily manipulated to unload the coke deposited in 25 it, and in which the platform receiving the coke is so formed that when portions of it are injured, as may happen from time to time, the injured portions may be readily replaced.

30 The various features of novelty which characterize my invention are pointed out with particularity in the claim annexed to and forming a part of this specification. For a better understanding of the invention, 35 however, and the advantages possessed by it, reference may be had to the accompanying drawings and descriptive matter, in which I have illustrated one of the forms in which the invention may be embodied.

40 Of the drawings: Figure 1 is an elevation showing the car and illustrating the manner in which it is manipulated to unload it. Fig. 2 is a sectional elevation of a portion of the car and of a portion of a coke oven structure in unloading which the car is employed, 45 the section of the car being taken on the line 2-2 of Fig. 8. Fig. 3 is a diagrammatic side elevation of the entire car. Fig. 4 shows a plan, and Fig. 5 a side elevation, of the 50 bars or platform units of which the platform or bed is composed. Fig. 6 is a perspective view of one portion, and Fig. 7 is a perspective view of the remaining portion, of the hinge connection between the car platform 55 and the running gear of the car; and Fig. 8

is a sectional elevation taken transversely to Fig. 2 on the line 8-8.

In the drawings, A represents the masonry body of a coke oven structure, B the framework understructure of the coke oven, and 60 C track rails running below the masonry portion of the coke oven structure and transversely to the direction in which the retorts A³ formed therein are horizontally elongated, the rails C being supported on the 65 understructure B. The car receiving the coke discharged from the retorts has wheels E² running on the rails C and comprises an underframe E and a platform or body portion G. In the form shown, the wheels E² 70 are driven through gearing E⁵ by cross shafts E⁶ which are driven in turn from the shaft E⁷ of the motor E⁹ mounted beneath the car, E⁸ representing the housing inclosing the gearing connecting the shafts E⁶ 75 and E⁷.

The platform G is hinge connected to the underframe E at both side edges to tilt relative thereto about one or the other of two axes located one above each rail C. The 80 hinge connections may be formed by bearings E¹⁰ (see Fig. 7) supported on the underframe E at its opposite side edges. Each of the bearings E¹⁰ is provided with a pintle E¹¹, the pintles of the various bearings at 85 each side of the underframe E being in alinement. Coöperating with each bearing member E¹⁰ is an open ended bearing member G¹ (see Fig. 6) secured to the underside of the platform G. Ears G² are provided at 90 the opposite side edges of the platform G, those at one edge or the other being engaged by suitable hoisting mechanism located at the place of discharge to tilt the platform G about the pintles E¹¹ at the opposite edge 95 of the platform when it is desired to discharge the coke into the coke receiving car or other receptacle at one side or the other of the track rails H¹ as shown in Fig. 1.

The platform G is provided with I-beams 100 G³ running parallel to the track rails C, upon which are removably placed the cast iron plates or bars G⁴, each provided with the ears G⁵ apertured or grooved to receive the upper flanged edges of a pair of beams 105 G³, as shown clearly in Figs. 4, 5 and 8. At each end of the platform G is located an inclined and preferably removable end portion G⁶, which comprises inclined beams G⁷ supported at their outer ends on saddle mem- 110

bers G⁹ resting on the transverse I-beams G⁸, and having their inner ends directly supported by the body of the platform G. On the rails or beams G⁷ are secured platform 5 bars G⁴ like those secured on the beams G³. The outer ends of the beams G⁷ are faced by end members G¹⁰.

With the construction shown, it will be observed that a broken or injured platform 10 bar G⁴ may be readily removed by sliding out the other bars G⁴ at one side of it which engage the same pair of beams G³ or G⁷. Preferably, to facilitate the removal of the 15 bars G⁴ the end portions G⁶ are secured to the body portion of the platform by readily detachable connections, not shown. The carriage underframe E may be protected from water employed in quenching by a floor or covering (not shown) between the platform 20 E and the bars G⁴ if thought necessary.

For the particular use illustrated, the hoisting mechanism M is provided for dropping the lower doors L of each coke oven retort A³ to bring the bottom edge of the 25 charge of coke to the level of the upper edge of the end portion G⁶ when the retort is to be discharged. The coke is then gradually discharged onto the platform G as the car is moved in the direction of the arrow

applied to Fig. 2. N represents a cover or 30 shield member employed to protect the inside of the coke oven structure from the heat of the coke discharged onto the platform G. No claim is made herein, however, to a coke 35 oven receiver or car with inclined ends, or to the cover N, or to hoisting mechanism 40 M, as these features of construction form a part of the subject matter claimed in my co-pending application Serial No. 398,901, filed October 24th, 1907, of which the present application is a division.

Having now described my invention, what I claim as new and desire to secure by Letters Patent is:

A receiver for hot coke discharged from 45 coke oven retorts, comprising a carriage body having parallel platform beams provided with lateral flanges and platform plates provided on their under side with apertures or grooves shaped to receive the 50 lateral flanges on said beams, whereby the flanges and beams are removably but positively secured together.

FREDERIC W. C. SCHNIEWIND.
